UNITED STATES PATENT OFFICE.

EDWIN E. SLICK, OF PITTSBURGH, PENNSYLVANIA.

METHOD OF FINISHING CAR-WHEELS.

1,111,622.

Specification of Letters Patent. Patented Sept. 22, 1914.

Application filed July 8, 1910. Serial No. 571,061.

To all whom it may concern:

Be it known that I, EDWIN E. SLICK, of Pittsburgh, in the county of Allegheny and State of Pennsylvania, have invented a new and useful Method of Finishing Car-Wheels, of which the following is a full, clear, and exact description, reference being had to the accompanying drawing, forming part of this specification.

10 This invention relates to the manufacture of forged metal car wheels and more particularly relates to finishing the wheels after the completion of the forging operations.

In the manufacture of metal car wheels 15 by forging, a fin, which may extend either wholly or partly around the periphery of the wheel is usually formed on the periphery of the wheel during such forging operations. In some methods of forming such wheels 20 the axle eye is formed in the wheel blank before the forging operations and in other cases the eye is formed in the hub of the wheel after the completion of the forging operation.

25 In certain methods of and apparatus for making car wheels by forging covered in Patent Number 965,035 and other patents issued to me on July 19, 1910, the wheels are forged upon a centering pin which extends

30 partly through the wheel hub and partly forms the axle eye during the forging, the axle eye being completed after the forging operation is finished. The fins formed on such wheels have heretofore been removed

35 by the use of slow speed rotary machine tools by which the fins are cut from the wheels, such operations being slow and expensive.

In cases where the wheel fit is formed by 40 boring the axle eye in the hub from the solid wheel hub, the expense of this operation adds largely to the cost of making the wheels.

One object of this invention is to provide an improved method of forming forged metal wheels by which the wheels are formed 45 upon a centering pin which does not extend entirely through the hub of the wheel, and to provide a novel method of finishing car wheels by which the opening through the hub of the wheel is completed after the forging operation in preparation for the boring operation by which the wheel fit is made.

Another object of the invention is to provide an improved method of finishing forged 50 wheels by which the fins formed on the periphery of the wheels are removed while the wheels are still hot from the forging op-

eration and in which the time required for removing the fins is very greatly reduced.

A further object of this invention is to provide an improved method of finishing 60 car wheels by which the wheels are completed after the forging operation in readiness for boring the wheel fit.

Referring to the drawings, Figure 1 is a side elevation showing apparatus constructed 65 and arranged and adapted for use in carrying out my improved method of finishing car wheels. Fig. 2 is a sectional detail, on a larger scale, showing the part of the apparatus of Fig. 1 employed to support a 70 wheel while the fin is being removed from its periphery. Fig. 3 is a detail section of the punching mechanism forming part of the apparatus shown in Fig. 1. Fig. 4 is a view similar to Fig. 3 showing the punching apparatus in position at the end of the hub punching operation. Fig. 5 is a sectional plan showing one way of holding the punching pins in place in the ram or plunger of the punching apparatus. Fig. 6 is a plan 80 and Fig. 7 is a sectional elevation of a forged car wheel as delivered from the forging apparatus to be finished in accordance with this invention.

In the drawings, referring to Figs. 6 and 85 7, a car wheel comprising a hub portion 2, a web portion 3 and tread and flange portions 4 and 5 is shown with a centering pin 6 in the hub 2, the end of the pin 6 being rounded and not extending entirely through 90 the wheel hub. An annular fin 7 is shown on the flange portion 5 of this wheel, which is located on the periphery of the wheel as delivered to the shear after the forging operation.

The wheels in this condition, preferably while still hot from the forging operation, are placed upon the carrier 8 which is rotatably mounted on one of the vertically extending tie rods 9 forming part of the punching apparatus, as is shown in Fig. 100

1. The carrier 8 is then rotated on the rod 9 so as to bring a wheel into the position relative to the rotary disks or knives 10 and 11, shown in Figs. 1 and 2. The disks or knives are then rotated, one of these disks being positively connected by slow down

105 gears 12 and 13 with the driving motor 14 shown in Fig. 1. It will be noted by reference to Fig. 2 that the wheels are placed, together with the pin which is centered in 110 the wheel support 14, upon the rotary carrier 8 in such manner that the wheel can

rotate about its own axis on the support 14^a during the fin severing operations. When the carrier 8 is rotated about its axis to bring the periphery of the wheel on the support 14^a into range of the rotary disks or knives 10 and 11, these knives or disks will engage with and sever the fin from the periphery of the wheel in one revolution of the wheel, the wheel being rotated by contact with the disks. After the severing operation is completed the carrier 8 is caused to rotate through another part of a revolution so as to bring the wheel from which the fin has just been removed into position above the anvil block 20 in range of the punching pin 15 of the punching mechanism, this pin then being in the position relative to the wheel shown in Fig. 3. The fluid pressure cylinder 16 is then supplied with fluid pressure so as to advance the ram 17 on which the pin 15 is mounted and move the pin 15 from the position shown in Fig. 3 into that shown in Fig. 4, by the downward movement of the punching pin completing the axle eye in the hub of the wheel and forcing the pin 18 from the wheel. While the hub of the wheel is being punched another wheel is being sheared. During the time the fin is being removed from a wheel, and another wheel is being punched, a punched wheel is being removed from the support 8 and a forged wheel which has just been completed, while still hot from the forging operation, is put into place on the support 8 in readiness to be moved into position to be sheared. The support as shown is equipped to hold three wheels, one in position to be sheared, one in position to be punched, and a third wheel which is being placed upon or removed from the carrier while the shearing and punching operations are being performed.

It is desirable to finish the wheels so that the hub length of successive wheels will be uniform, and in order to accomplish this result, means are provided, which, as shown in Figs. 3 and 4, consist in a die face 19 removably supported on the stripping mechanism 20^a. When the ram 17 is advanced so as to complete the axle eye in the hub of the wheel and after the eye is completed and the pin 18 removed from the hub of the wheel, the downward movement of the ram 17 is continued until the lower end of the ram engages with the stripper 20^a. By continuing the downward movement of the ram with the stripper 20^a the die face 19 is moved from the position shown in Fig. 3 into that shown in Fig. 4, this movement continuing for the full length of the stroke of the ram 17 and fixing the length of the axle eye of the wheels.

It will be noted that the support 14^a is held out of engagement with the top face 65 of the carrier 8 as is shown in Figs. 2 and

3 and that the lower face of the support 14^a does not contact with the top face of the anvil block 20 while the support 8 and carrier 14^a are being moved into position above the anvil block. When the ram is advanced so as to begin the operation of completing the axle eye the lower face of the support 14^a is moved into contact with and is supported by the top face of the anvil block 20 during the punching or eye-forming movement, this being clearly shown in Fig. 4.

In some cases wheels will be forged with the axle eye formed therein and in other cases the wheels may be forged and the wheel formed, and the wheels afterward re-heated and the fins removed. In such cases, there not being a pin in the axle eye, it will be necessary to place the wheel upon a pin so as to center it on the support 8 during the shearing operation. In such cases I preferably employ a pin 18^a such as is shown in Fig. 2, this pin being removably secured in and forming part of the support 14^a, and the wheel being placed upon the pin on the support before moving the support 8 and carrier 14^a to bring the wheel into shearing position relative to the shear knives 10 and 11.

As wheels of various diameters will be sheared with the same mechanism, means are provided for adjusting the shear toward and away from the support 8. In the case shown, this adjustment is secured by the screw 21, which is operatively connected to the base 22 of the shear.

The advantages of my invention will be apparent to those skilled in the art. By the use of my improved method the hubs of the wheels are completed in readiness for the boring operation by which a wheel fit is made, fins formed during the forging operations are quickly removed, and the hubs are sized to a fixed definite length at the same heat by which the forging operation is carried out. The necessity for a later number of slowly operating turning operations by means of slow speed machine tools is removed and the cost of making forged wheels is largely reduced.

I claim:

1. In the manufacture of forged steel wheels the sequential steps consisting in centering the forged wheel upon a support, then bringing the centered wheel into engagement with the cutting members of a shear to thereby sever peripheral fins from the centered wheel, then shifting the support to bring the centered wheel into range of a punch, and punching the centered and sheared wheel to form the eye in the hub of the sheared wheel.

2. In the manufacture of forged metal wheels the sequential steps consisting in centering the forged wheel upon a support,

then bringing the centered wheel into engagement with the cutting members of a shear to thereby sever peripheral fins therefrom, and then shifting the support to bring said wheel into range of a punch, and punching the hub of the centered wheel to form the axle eye in the hub of the sheared wheel.

3. In the manufacture of forged metal wheels the sequential steps consisting in centering the forged wheel upon a support, moving the support to bring the wheel into engagement with a shear and thereby severing the fin from the periphery of the wheel, shifting the support to bring the centered wheel into range of a punch, and then punching the wheel to form an axial opening through the wheel hub, and simultaneously reducing the hub length to a predetermined size in the punching operation.

4. In the manufacture of forged metal wheels the sequential steps consisting in centering the forged wheel upon a wheel support, rotating the support to bring the centered wheel into engagement with opposing rotary disks and rotating the centered wheel on the support when engaged by the disks in removing the fin from the periphery thereof, then moving the support to bring the centered wheel into range of a punch, and punching the wheel to form an axially central opening extending through the wheel hub.

5. In the manufacture of forged metal wheels the sequential steps consisting in centering a forged wheel upon a wheel support, then bringing the centered wheel into engagement with the cutters of a rotary shear, rotating the wheel on the support while engaged by said cutters and thereby removing the peripheral fin from the wheel, then shifting the support to bring the wheel into range of a punch and then actuating the punch to form an opening in the wheel hub and reduce the wheel hub to a predetermined length.

6. In the manufacture of forged metal wheels the sequential steps consisting in centering a heated wheel having a pin in the hub thereof upon a support, moving the support to bring the wheel into range of a punch and punching the hub thereof to remove the pin and form an axially extending opening in said wheel.

55 7. In the manufacture of forged metal wheels the steps consisting in centering a heated wheel upon a wheel support, moving the support to bring the centered wheel into alinement with a punch and actuating said punch to form an axially extending

opening in the wheel hub and reduce the hub to a predetermined length.

8. In the manufacture of forged metal wheels the steps consisting in centering a heated wheel having a pin in the hub thereupon a movable support, shifting the support to bring the wheel into axial alinement with a punch, and then actuating the punch to remove the pin and form an axially extending opening in the wheel hub and reduce said hub to a predetermined length.

9. In the manufacture of forged metal wheels, the sequential steps consisting in forging a wheel upon a centering pin, then centering the wheel and pin upon a support, then bringing the centered wheel into engagement with a rotary shear to thereby sever the peripheral fin therefrom, and then shifting the support to bring the centered wheel into range of a punch and actuating said punch to remove the pin and form an axially extending opening through said wheel hub.

10. In the manufacture of forged metal wheels the sequential steps consisting in forging a wheel upon a centering pin, then centering the wheel and pin upon a support, then bringing the centered wheel while still heated from the forging operation into engagement with a rotary shear to thereby sever the peripheral fin therefrom, then shifting the support to bring the centered wheel into range of a punch and while the wheel is still heated actuating said punch to form an axially extending opening through said wheel hub and reduce said hub to a predetermined length.

11. In the manufacture of forged metal wheels the steps consisting in forging a wheel upon an axially central pin, centering the forged wheel upon a support, moving the support to bring the centered wheel into range of a punch and actuating the punch to remove the pin and form an axially extending opening through the hub of said wheel.

12. In the manufacture of forged metal wheels the steps consisting in forging a wheel upon an axially central pin, centering the forged wheel upon a support, moving the support to bring the centered wheel into range of a punch and actuating the punch to remove the pin and reduce the wheel hub to a predetermined length.

In testimony whereof, I have hereunto set my hand.

EDWIN E. SLICK.
